UNITED STATES PATENT OFFICE.

EDWARD E. WAKEFIELD, OF PROVIDENCE, RHODE ISLAND, ASSIGNOR TO TUBULAR-RIVET & STUD COMPANY, OF PROVIDENCE, RHODE ISLAND, A CORPORATION OF MASSACHUSETTS.

LACING-STUD-SETTING MACHINE.

1,328,701.

Specification of Letters Patent. Patented Jan. 20, 1920.

Application filed September 19, 1917. Serial No. 192,043.

To all whom it may concern:

Be it known that I, EDWARD E. WAKEFIELD, a citizen of the United States, and resident of the city of Providence, in the county of Providence and State of Rhode Island, have invented certain new and useful Improvements in Lacing-Stud-Setting Machines, of which the following is a specification.

10 This invention relates to improvements in machines for automatically setting lacing studs such as hooks or eyelets in shoe uppers and the like, and has for its object to provide means coöperating with the 15 hook-setting means for feeding a strip of reinforcing material to be connected to the shoe upper by the setting of studs through both, and this invention is an improvement on my Patents No. 1,129,030 of February 16, 20 1915 and No. 1,234,982 of July 31, 1917.

A further object of this invention is to provide means for partially severing the strip at intervals and then completely severing the same after a predetermined number 25 of partially severing operations, whereby the strip when laid upon and connected to the upper, may be caused to more readily conform to the curvature of the upper without wrinkling or buckling the stiffened 30 backing material and still retain a portion of its reinforcing strength along the outer edge of the upper.

With these and other objects in view, the invention consists of certain novel features 35 of construction, as will be more fully described, and particularly pointed out in the appended claims.

In the accompanying drawings:

Figure 1— is a front elevation of the 40 feeding head partly in section showing the presser foot in engagement with the shoe upper, the reinforcing tape as being fed and secured to the upper and my improved means for severing or partially severing 45 the strip before being connected to the upper.

Figure 2— is an enlarged view looking 50 from the left of Fig. 1 toward the multiple edged cutter and the face of the cutter-block, the punch plunger being removed to better show the cutter in raised position, and illustrating the pawl which engages and rotates the cutter each time the punch plunger rises after having set a stud.

Fig. 3— is a side elevation showing the

punch plunger and cutter in the down position illustrating the pawl in position to engage and rotate the cutter blades upon the next upward motion of the plunger.

Fig. 4— is a sectional edge elevation 60 showing the spring-pressed ball detent for engaging the cutter-plate and preventing a retrograde or backward motion of the cutter while the pawl is being dragged over its arm as the cutter descends on its operating stroke.

Fig. 5— shows a length of backing strip as being partially severed at intervals and finally completely severed from the rest of the strip after a predetermined number of 70 stud-setting operations.

Fig. 6— illustrates this width of backing strip as applied to a shoe upper.

In the accompanying drawings I have illustrated such portions of a hook-setting 75 machine as is necessary to illustrate my present invention, but my improved mechanism is as well adapted for use on an eyelet-setting machine, as the strip may serve equally well as a reinforcement for a hook 80 as for an eyelet, and I have therefore adopted the term "lacing stud" and have used the same throughout the specification and claims, which term includes both the hook and the eyelet.

I have herein shown and described only sufficient mechanism to set forth my present invention.

In the drawings, 10 designates a portion 90 of the carriage frame in which is mounted the punch-spindle 11 and the presser-foot spindle 12, the latter spindle being supported from the frame 10 by the guide block 13 and also by the collar 14. To this spindle 11 is connected the punch 15 which forms 95 holes in the upper *b* and also in the strip of stiffened reinforcing tape 16 for the reception of the lacing studs 17.

The cutter plate 18 is formed preferably 100 in somewhat of a star shape, see Fig. 2, comprising a plurality of radiating arms 20, each having a cutting edge 19 formed at its outer end, blades 21, 22 and 23 being of a width to but partially sever the strip, cutting inward from one edge thereof and leaving a narrow uncut portion along the opposite edge while the blade 24 is of a width sufficient to completely sever the strip.

This cutter plate is rotatably mounted on 110 a central pivot 25 which passes through it

and the downwardly extending supporting plate 26 fixed to the collar 14 best illustrated in Fig. 3.

In order to rotate this cutter blade at the proper time I have provided a spring-wire pawl 27 fixed at its upper end to the guide-block 13 and arranged to extend down through a hole in the reciprocating collar 14, its end 28 being arranged to engage the upper edge of the arm which projects outwardly beyond this pawl, whereby as the plunger rises, the pawl end engages this arm causing the whole plate to rotate and finally the end 28 of the pawl rides outward on the shoulder 29 of the arm, thereby carrying the cutting edge of its arm around parallel with the face of the reinforcing strip ready to cut the same. As the punch plunger descends with its knife blade, it will be seen that the pawl end snaps over the next laterally-extending arm and is then in position to engage this arm and rotate the cutter upon the next upward motion of the plunger, and so the knife blades are rotated step by step each time the plunger rises.

It is found that as the point of this pawl is being dragged over the next cutter arm, that it has a tendency to rotate the cutter in a backward direction, to prevent which action I have provided a spring-pressed detent 30 in the form of a ball, see Fig. 4, which sets in the recess 31 in the plate 26 and is forced by pressure of the spring 32 into the recess 33 in the back of the knife blade, thereby serving to hold the blade against the friction of the pawl as it is dragged over the cutter arm.

I do not wish to limit myself to the use of a rotating cutter as any style of cutter adapted to partially sever the strip for a predetermined number of times and then completely sever the same, will fall within the spirit and scope of this invention.

The guide-block 34 is connected to the presser foot spindle 12 and is provided with a longitudinal aperture 35 through it which serves as a guide through which the strip 16 passes, and by which the strip is accurately conducted over or to the upper which it is to be laid upon and connected in the desired position thereto by the setting of studs through both.

The outer edge of this block is provided with a hardened plate 36 having an aperture through which the tape also passes and this plate serves to coöperate with the various edges of the cutter 18, whereby the latter is caused to slide upon that of the former to sever or partially sever the strip passing through the block.

In the operation of my improved device the tape 16 is led from a roll (not shown) through a suitable guide 37 supported from the arm 38 which is connected to the presser

foot 39, see Fig. 1. In this guide I have mounted a tension spring 40 which permits the tape to advance but prevents the same from moving backward during the return stroke of the feeding mechanism. From 70 this guide the tape is led through the aperture in the guide block 34 above the engaging surface of the presser foot and over the cutting edge of the cutter-plate 36.

In setting the machine for the operation 75 of applying a backing strip to the upper b, the end of the strip is advanced by hand beyond the cutting edge of the block 34 beneath the punch 15. The punch now descends piercing the strip and the upper, the 80 strip being partially severed by the blade 18 and then with a lateral motion moves both the strip and upper to the left into the next position over the pocket-plate 41, which latter coöperate with the punch to set 85 and rivet the studs in the upper and at the same time secures the reinforcing strip to the back thereof. The punch spindle is now raised and moved to the right a distance equal to that between the studs, while the 90 upper is held in fixed position by the presser foot which in turn holds the partially severed strip riveted thereto. The operation above described is repeated at the setting of each stud, the movement of the head to the 95 left serving to draw out the strip and the setting of the studs secures the strip to the upper to be advanced therewith.

It will be seen from the above description of the knife that each downward 100 stroke of the plunger causes the knife to partially sever the strip and that on the last upward stroke of the plunger before the setting of the last stud into the upper, the broadest cutter-plate 24 of the lot is moved 105 into position so that this last downward stud-setting stroke completely severs this length of strip from the balance thereof, which stroke sets the last stud finally securing the severed length of strip to this 110 upper. The upper is now removed from the machine and another positioned therein and the presser foot lowered to retain the same.

The next movement of this head in beginning its operation upon the fresh upper is to the right, which causes the strip to extend the desired distance beyond the punch. The next operation forces the spurs or needles 42 into the strip and the punch 120 downward through the projecting end of the strip and the operation of setting the studs in this upper is repeated in the manner above described.

I have shown and described one form of 125 mechanism by which a length of the reinforcing strip may be severed at intervals and finally completely severed from the main strip, but any mechanism for accomplishing this function will fall within 130

the spirit and scope of my invention as I reserve the privilege of resorting to all the mechanical changes to which the device is susceptible, the invention being defined and limited only by the terms of the appended claims.

I claim:

1. In a lacing stud setting machine, means for advancing a reinforcing strip step by step to be attached to the work, a rotatable cutter having a plurality of blades, and means for automatically adjusting said blades to partially sever at intervals and completely sever the strip after a predetermined number of partially severing operations.

2. In a machine of the character described, means for advancing a reinforcing strip to be attached to the work, a rotatable cutter having a plurality of blades for partially severing the strip at intervals and completely severing the strip after a predetermined number of partially severing op-

erations, a pawl for engaging and automatically rotating said cutter after each cutting operation, and means for preventing a retrograde motion of the cutter after having been advanced by said pawl.

3. In a lacing stud setting machine, feeding means for simultaneously advancing the work and a reinforcing strip step by step to receive a stud through both, a pivotally mounted rotatable cutter having blades of different widths for partially severing the strip at intervals, a spring pawl for rotating said blades to present a fresh one after each cutting operation and finally presenting a wide blade for completely severing the strip after a predetermined number of partially severing operations.

In testimony whereof I affix my signature in presence of a witness.

EDWARD E. WAKEFIELD.

Witness:

HOWARD E. BARLOW.
